ELWOOD C. HALL, OF VIENNA, NEW JERSEY

STRIKING CLOCK

Original application filed July 9, 1928, Serial No. 291,320. Divided and this application filed November 5, 1929. Serial No. 404,958

This invention relates to a striking clock, the present invention being a division of the application filed by me on July 9, 1928, Serial No. 291,320.

5 The general object of this invention is to provide ratchet means for controlling the operation of the striking train of the clock, with means for controlling the operation of the ratchet means by a snail or toothed cam 10 on the hour arbor of the clock, so as to effect a progressive sequence of strikes for the successive hours and also to so arrange and construct the parts that the re-setting of the hands will not interfere with the striking mechanism.

15 This invention also consists in certain other features of construction and in the combination and arrangement of the several parts, to be hereinafter fully described, illustrated in the accompanying drawing and specifically pointed out in the appended claims.

20 In describing the invention in detail, reference will be had to the accompanying drawing wherein like characters denote like or corresponding parts throughout the several views, and in which:—

25 Figure 1 is a fragmentary elevation of the invention, with sufficient parts of the clock to show the cooperation of the several parts, this figure showing the striking train held against movement.

30 Figure 2 is a similar view but showing the parts with the striking train in operative position.

35 Figures 3 and 4 are views similar to Figure 2, but showing the parts in different positions.

40 Figure 5 is an end view as seen from the left side of Figure 1.

In these views, the numeral 1 indicates a disk placed on the minute arbor 2 of the clock and carrying a notched pawl 3 which is normally held against a pin 4 on the disk 45 by a spring 5. An hour arbor 2' carries a snail or toothed cam 6 which is constructed as shown. An arbor 7 is rotatably arranged in the clock frame and carries the arms or wires 8, 9 and 10. The arm 8 carries 50 an arc-shaped rack 11 which is provided with

sixteen teeth which are adapted to be engaged by a pin 12 on the hub of a wheel 13 which forms part of the striking train of the clock. The arm 9 is formed with a flat part 9' which is adapted to engage a pin 14 on the wheel 13 and thus hold the wheel and, therefore, the striking train, in inoperative position, as shown in Figure 1. The arm 10 is formed with a hook 10' for engaging the teeth of the cam 6. A holding pawl 15 is pivoted to part of the frame and engages the teeth of the rack to hold the same against retrograde movement when the rack is being lifted step by step by the pin 12 on the wheel 13.

An arbor 17 is rotatably arranged in the frame and carries the arms or wires 18, 19 and 20. The arm 20 has its free end adapted to be engaged by the pawl 3 once every revolution of the disk, which, of course, is once every hour, and when this occurs, the three-arm assembly will be lifted so that the arm 18 will engage the dog 15 and gradually raise the same out of engagement with the rack on the stroke of the hour, so that the rack and the assembly arms 8, 9 and 10 will drop until the hook 10' of arm 10 strikes the cam 6. As the rack and the arms drop, the arm 9 will free the pin 14 so that the wheel 13 and the striking train can begin to operate and on each revolution of the wheel 13, the pin 12 will engage a tooth of the rack and lift the rack one step. A projection 21 is carried by one of the spokes of the wheel 13 and will engage the end of the arm 19 55 at the beginning of the movement of the wheel 13, which acts to lift the parts to a position where the arm 20 will be moved out of engagement with the dog 3 so that the spring of the dog can return to normal position and then the end of the arm 19 drops below the projection 18, so that the wheel can rotate.

Figure 1 shows the parts in inoperative position or in the position they occupy after the striking operation has ceased. Then when the dog 3 engages the arm 20, the arm 18 will move the holding dog 15 to releasing position and the arm 9 will be positioned where its end can be engaged by the projec- 100

tion 21. The rack 11 will then drop until the bent end of the arm 10 engages a step of the cam 6, as shown in Figure 2, and the arm 9 frees the wheel 13, so that said wheel can begin to rotate. At the first part of this rotation, the projection 21 will engage the arm 19 and move the parts to a position where the arm 20 is out of engagement with the dog 3, so that the spring of the dog can return to its normal position, as shown in Figure 3. As the arm 19 is freed of the projection 21, the lever system drops to the position they occupy in Figure 4, and thus at each revolution of the wheel 13, the pin 12 will engage a tooth of the rack 11 and raise it one tooth and this will continue until the rack has been moved to the position it occupies in Figure 1, when the arm will engage the pin 14 and thus stop further rotation of the wheel 13, so that the striking operation ceases. As will be understood, the position of the arm 10 on the cam 6 will control the amount of drop of the rack 11 and this, in turn, controls the number of strikes of the clock, it being understood that each revolution of the wheel 13, which is connected with the striking train, will cause the striking mechanism to operate once. As will be understood, the rack 11 and its supporting means, with the wire or arm 10 and the cam or snail, forms part of the mechanism now in use on Grandfather clocks.

It is thought from the foregoing description that the advantages and novel features of the invention will be readily apparent.

35 It is to be understood that changes may be made in the construction and in the combination and arrangement of the several parts, provided that such changes fall within the scope of the appended claims.

40 What I claim is:—

1. An interrupter for a striking clock, comprising a dog on the minute shaft of the time train of the clock, a wire system actuated hourly thereby, a wheel forming part of the alarm train of the clock, a projection on said wheel, a rack, a second wire system supporting the rack and comprising a part for engaging said projection for holding said alarm train against movement and another part for engaging a snail, a holding dog for the rack, means whereby a part of the first wire system will move the holding dog to releasing position when the wire system is actuated, a snail on the time movement for engaging said snail engaging part of the second wire system, a projection on a wheel of the alarm system for engaging another part of the first wire system for releasing the dog on the minute shaft from its engaging member and a pin on the hub of the alarm gear for engaging the teeth of the rack.

2. In combination with a clock including its alarm train and time train, a wheel connected with the alarm train; a pin on the hub 65 of the wheel, a pin on the rim of the wheel

and a projection on a spoke of the wheel, an assembly of three arms pivotally arranged in the clock, a rack carried by one arm, the end of the second arm being adapted to engage the pin on the rim for holding the wheel and the alarm system against movement, a snail connected with the time train, the third arm of the system being adapted to engage said snail, a second assembly of three arms pivotally supported in the clock, a holding dog 70 for the rack, a pivoted dog on the minute shaft engaging one of the arms of the second system for raising the arms to cause one arm to move the holding dog to releasing position and another arm into the path of the projection on the spoke whereby the third arm will be moved out of engagement with the dog on the minute shaft, the pin on the hub engaging the teeth of the rack for moving the rack step by step at each revolution of the wheel 85 until the before mentioned second arm of the first assembly engages the pin on the rim of the wheel to prevent further movement of the wheel, the engagement of the snail with the third arm of the first assembly regulating the distance the rack drops when the holding dog is moved to releasing position.

In testimony whereof I affix my signature.

ELWOOD C. HALL.
